UNITED STATES PATENT OFFICE.

GEORGE T. NEWELL, JR., OF PASSAIC, NEW JERSEY, ASSIGNOR TO VESTA MANUFACTURING COMPANY, OF PASSAIC, NEW JERSEY, A CORPORATION OF NEW JERSEY.

WATER-HEATER.

1,103,614.

Specification of Letters Patent.

Patented July 14, 1914.

Application filed August 9, 1913. Serial No. 783,885.

To all whom it may concern:

Be it known that I, GEORGE T. NEWELL, Jr., a citizen of the United States of America, residing at Passaic, Passaic county, 5 in the State of New Jersey, have invented certain new and useful Improvements in Water-Heaters, of which the following is a full, clear, and exact description.

This invention relates to portable water-heaters more particularly to the heating-coils thereof, and has for its object, among others, to provide for use in such water-heaters an inexpensive heating-coil of special construction and arrangement whereby 10 space is economized and a maximum amount of heating surface provided and in which the coils or convolutions are so disposed that air currents or flues are practically obviated.

20 The particular features of improvement and some of the advantages flowing therefrom will be hereinafter described more in detail and finally set forth in the appended claim, reference being had to the accompanying drawing, forming part hereof, wherein—

Figure 1 is a side elevation, partly in section, of a water heater embodying my improvements, and Fig. 2 is a sectional plan 30 view thereof, the section being taken on line 2—2 in Fig. 1.

In the accompanying drawing, the numeral 1 indicates the casing of a water heater, within which is contained a heating 35 coil preferably composed of a single tubing of copper, looped or convoluted, as shown, one terminal of the coil constituting the inlet 3 and the other terminal the outlet 4. It will be seen that the coil is bent into a series 40 of contiguous juxtaposed loops or convolutions, 5, arranged in substantially horizontally disposed superposed layers 6 to 17, respectively. The inlet end of the coil, it will be noted, passes from the upper portion of 45 the casing in a horizontal plane toward the left and then bends downwardly and through the end loops to provide a vertical portion 18, and near its bottom it again is bent as at 19 to run in a horizontal plane, 50 and is then looped or convoluted as at 20, and again looped as at 21, forming two additional loops; it is then looped again as at 22, to form two more additional loops, and then 55 looped as at 23 to form two more loops, (the opposite side of this lowest layer of loops 21

22 and 23 appearing in the form of contiguous duplex-loops); it is then looped as at 24, 25, 26, 27 and 28, all the loops being arranged in substantially contiguous superposed relationship, and so on until a sufficient number of layers of coils or loops is provided. It will be seen (Fig. 1) that the convolutions or loops of alternate layers are oppositely directed relatively to each other, that is to say (for instance) the loops 60 formed by the coils, 21, 22 and 23 are directed oppositely to the direction of the loops 24, 25, 26, 27 and 28. Within the casing and at each side thereof, are supporting standards 29 and 30 provided with spaced 65 lugs or projections 29^a and 30^a, upon which the layers of loops may rest and whereby also the same are kept in spaced relationship. The coils are heated by a suitable burner 31.

75 Although in the drawing I have shown the layers of loops as spaced apart to a substantial degree, I have shown the same thus spaced for the purpose of more clearly illustrating the arrangement of the coils or loops, 80 as in practice the layers of loops are more closely nested and the spacing lugs more closed disposed. It will, therefore, be understood that the particular degree of spacing or nesting of the layers can be arranged 85 to suit requirements.

It will be noted that the inlet starts at the upper portion of the heater and the water runs downwardly so that incoming water will be first heated at the lower portion of 90 the tubing, and thus the water is heated from the bottom upwardly to the top or outlet. I have found in practice that by this arrangement undue condensation is avoided. It will also be noted that by my arrangement of the layers of coils or convolutions a 95 comparatively large heating surface is provided, as substantially all the parts are exposed to the heat. Furthermore, it will be seen (Fig. 2) that the respective loops or 100 convolutions of one layer are staggered relatively to the loops of the adjacent superposed layers. This arrangement leaves no flues and air currents are consequently broken up. Furthermore, great economy of 105 space is provided. In heating coils provided with continuous vertically arranged spiral-like convolutions, air currents or drafts are more apt to take place than in the construction which I have shown and described.

Having now described my invention, what I claim and desire to secure by Letters Patent is:

A water heater comprising a casing, a
5 burner arranged therein, and a water pipe
leading into the casing near the upper end,
projected laterally, then downwardly and
laterally adjacent the burner, and projected
upwardly therefrom in a series of superim-
10 posed layers extending across the casing,
each layer inclining upwardly from the in-
let end thereof to the outlet end thereof,
each layer including a series of successive

coils, the lowermost section of each coil be-
ing on an upward inclination with respect 15
to the uppermost section of the adjacent
coil toward the inlet of the particular layer,
whereby the flow of water throughout the
layers is continuously against the action of
gravity. 20

Signed at New York city, N. Y., this 8th
day of August, 1913.

GEORGE T. NEWELL, JR.
